UNITED STATES PATENT OFFICE.

WILLIAM J. DENNIS, OF CHICAGO, ILLINOIS.

WEATHER STRIPPING.

Application filed November 8, 1926. Serial No. 147,008.

My invention relates to new and useful improvements in weather stripping and more particularly to that type of weather stripping which is especially applicable to doors, windows or the like, and has for its object to provide weather stripping of this character which may be readily applied to a window or door to create a tight fit between the said window or door and the casing therefor and prevent rattling.

Another object of my invention is the provision of a weather stripping of the above character which can be economically and readily applied, and when in applied position will prevent the admission of dust, cold air, rain or snow around the window or door.

A further object of my invention is the provision of weather stripping which is formed with a novel and efficient attaching flange, whereby when the securing means is applied thereto it will have a tendency to force the body of the strip into close fitting contact with the door or window and at the same time prevent the flange from becoming displaced, or the tearing or distortion of the flange by the securing means.

To this end, my invention consists in the novel construction, arrangement and combination of parts herein shown and described, and more particularly pointed out in the claims.

In the drawings, wherein like reference characters indicate like or corresponding parts:

Fig. 1 is an elevation of a window illustrating the application of my improved weather stripping;

Fig. 2 is a detail section on the line 2—2 of Fig. 1;

Fig. 3 is a detail section taken through a door casing and a portion of a door, illustrating the application of my improved weather stripping;

Fig. 4 is a perspective of a portion of the weather stripping;

Fig. 5 is a transverse sectional view;

Fig. 6 is a view similar to Fig. 5, illustrating a slightly modified form of stripping;

Fig. 7 is an enlarged view similar to Fig. 6, illustrating still another form of the invention;

Fig. 8 is a detail transverse section illustrating that form of the invention shown in Fig. 7 in an applied position; and

Fig. 9 is an enlarged transverse section with the reenforcement for the flange omitted.

In carrying out my invention, I prefer to provide a filler body of yieldable packing material such as a rope of cotton, hemp, jute or other material suitable for the purpose, said body being enclosed with a flexible cover sheet having its edges extending beyond one side of the body and folded to form a securing flange.

In the present instance, Figs. 1 to 5 inclusive illustrate the preferred embodiment of my invention and include in its construction the selection of the type of filler body to be preferred, said body being indicated at 1 and the cover, which is of flexible material, is generally indicated at 2. This cover may be of rubber, rubberized cloth or any other similar material cut in strips of suitable length and width and folded longitudinally around the filler body 1 so that the body 1 is preferably positioned within the fold and the edges of the strip are arranged in parallel relation, one of the edges preferably extending beyond the other edge so that when these edges are folded upon themselves as shown in Fig. 5, the extremities of the edges will be brought into close fitting engagement with the main fold of the body strip as shown at 3 by having said edges extending onto and conforming to the contour of the body as is clearly illustrated in Figs. 7 and 9.

From the foregoing it will be apparent that by arranging the edges of the cover strip in parallel relation and then folding them upon themselves, a substantially four-ply securing flange is formed as indicated at 4. In order to increase the strength of the flange so as to prevent the same from becoming easily torn or mutilated by the securing means and also to prevent warping or bulging of the outer edge of the flange, a reenforcing element 5 is positioned within the folded over portion of the edges of the cover strip as shown in Fig. 5. This reenforcing may be a small rope of cotton, hemp or the like, or may be of wire, rubber or any other material suitable for the purpose. After the edges have been folded over and the extremities thereof brought in close engagement with the main fold of the body strip, they are stitched together as shown at 6, said line of stitching being disposed in close proximity to the filler body 1 so as to securely enclose the filler body within the cover sheet and at the same time im-

part a certain amount of rigidity to the flange formed by the plies 4.

It will be apparent that as the filler body 1 is of comparatively flexible or yieldable material and the cover of a similar nature, the weather stripping can be placed in close proximity or into tight fitting engagement with the door or window so as not to interfere with the operation of the same but at the same time prevent the entrance of dust, cold air, rain or snow around the window or door. It will also be apparent that by placing the reenforcing element 5 within the double fold of the edges of the cover strip, the outer edge of the flange defined by the plies 4 will be increased in stiffness so that when the securing elements such as tacks or the like are passed through the flange to secure the same to a door or window frame, the reenforcing element will cause the outer edge of the flange to lie in close proximity to the frame and thus prevent the outer edge of the flange from drawing away from the frame and at the same time will reenforce the edge of the flange to such an extent that it will prevent the securing means from being torn laterally through the edge of the flange. With certain types of securing means, the edges thereof may be lapped over the folded portion in which the reenforcing element is placed so as to bring the edge of the flange into close tight-fitting engagement with the frame upon which it is placed and securely retain the same in its effective position.

It may be found desirable in a great many instances to eliminate the reenforcing element 5, as shown in Fig. 9, and in this case the securing elements which are used to attach the flange to the window or door frame are passed through the flange at a point intermediate the outer edge of the flange and the body, the double folded portion of the parallel edges of the cover strip forming sufficient reenforcement for the outer edge of the flange to prevent the flange from being torn from the securing elements and the securing elements may be of such nature as to bring the double folded portion of the flange into tight fitting engagement with the surface to which it is applied in such manner that the outer edge of the flange will not draw away from the surface or permit it to bulge.

In Fig. 5 the reenforcing element is illustrated in the form of a rubber core, while in Fig. 6 the reenforcing element 5' is shown in the form of a rubber tube, while in Figs. 7 and 8 the reenforcing element 5^a is illustrated in the form of wicking.

In Fig. 8 I have illustrated in detail cross section the manner in which the flange and a portion of the body cover is brought into close contact with a window or door frame, and it will be noted that with securing means of this type, which is in the form of large headed tacks 7, the heads of the tacks will

span the space between the cover of the body filler 1 and the folded over portion which surrounds the core 5^a, thus bringing both the reenforcing element and the body stripping close to the surface to which it is applied, and by arranging the longitudinal edges of the cover strip in parallel relation and folding them over as set forth above, it provides a substantially four-ply flange which reduces to a minimum the accidental tearing or distortion of the flange itself and the reenforcing element adds to further prevent such tearing or distortion. 70 75

As stated above, one of the edges of the cover sheet extends beyond the other edge so that when these two edges are folded upon themselves, the outermost or longer edge will lap over the extremity of the shorter edge and thus permit these extreme outer edges to be fitted closely within the curvature between the main loop portion of the body and the edges thereof as shown at 3. Thus, after the line of stitching 6 has been passed through the four plies of the flange, these extreme edges will be brought into close fitting engagement with the exterior of the body so as to provide a neat appearance for the article itself. 80 85 90

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned. 95 100

One of the particular features in the construction of weather stripping along the above lines is that the rubberized surface of the material used is always exposed to the weather and that the loose edges of the material which are connected to the flange part by the stitching 6 is arranged next to the wood-work upon which the stripping is attached so that it eliminates any possibility of the elements entering between the sheets forming the covering and coming in contact with the unrubberized side of the material. 105 110 115

What I claim as new and desire to secure by Letters Patent is: 115

1. A weather stripping including a body of yieldable material, a cover sheet enclosing the body with its edges arranged parallel and folded upon themselves to form a flange, means for connecting the folded portion of the edges at a point adjacent the body, the extreme longitudinal edges of the folded portions extending onto and conforming to the contour of the body, and a reenforcing element within the outer fold of the edges to increase the rigidity of the flange. 120 125

2. In a weather stripping of the kind described, a yieldable body, a cover sheet enclosing said body and having its longitudinal edges extended transversely of said body, 130

- said extended portions in contact with each other, a reinforcing element spaced from and disposed substantially parallel to said yieldable body, said extended edges folded backward toward said body portion enclosing said reinforcing element and terminating adjacent and conforming to the contour of said body portion to form a four-ply nailing flange with said reinforcing element enclosed in the outer edge of said flange, and a single row of stitching through said four-ply structure adjacent said body portion. 5
3. In a weather stripping, a yieldable body, a cover sheet enclosing said body and having its longitudinal edges extending transversely of said body, said extended portions in contact with each other, said extended edges folded backward toward said body portion so as to form a marginal bead therein and terminating adjacent and conforming to the contour of said body portion to form a nailing flange, and a single row of stitching through said structure adjacent said body portion. 10
4. In a weather stripping, a yieldable body, a cover sheet enclosing said body and having its longitudinal edges extending transversely 15
- of said body, said extended portions in contact with each other and folded backward toward said body portion to form a marginal bead and terminating adjacent and conforming to the contour of said body portion to form a four-ply nailing flange, the outermost of said edges overlapping the innermost edge, and a single row of stitching through said four-ply structure adjacent said body portion. 20
5. In a weather stripping, a yieldable body, a cover sheet enclosing said body and having its longitudinal edges extending transversely of said body, said extended portions in contact with each other and folded backward toward said body portion to form a marginal bead and terminating adjacent and conforming to the contour of said body portion to form a four-ply nailing flange, the outermost of said edges overlapping the innermost edge, a single row of stitching through said four-ply structure adjacent said body portion, and reinforcing means disposed in said marginal bead. 25

In testimony whereof, I have hereunto signed my name.

WILLIAM J. DENNIS.
